UNITED STATES PATENT OFFICE.

FREDERICK B. WISCHHUSEN, OF HOUSTON, TEXAS.

STAMPING-MACHINE.

1,339,050.

Specification of Letters Patent.

Patented May 4, 1920.

Application filed June 21, 1919. Serial No. 305,839.

To all whom it may concern:

Be it known that I, FREDERICK B. WISCHHUSEN, a citizen of the United States, residing at Houston, in the county of Harris and 5 State of Texas, have invented certain new and useful Improvements in Stamping-Machines, of which the following is a specification.

This invention relates to new and useful 10 improvements in a stamping machine.

One object of the invention is to provide a device of the character described which has been specially designed for the purpose of stamping nuts, particularly walnuts. 15 In marketing nuts, it is customary for the seller to stamp each nut with a particular trademark or design, and this is a tedious and laborious undertaking when the nuts are stamped by hand singly. The machine 20 herein described has accordingly been designed for the purpose of accurately and rapidly stamping the nuts automatically and in quantities.

Another object of the invention is to provide 25 a machine of the character described, whereby the nuts may be rapidly stamped, with any desired mark or design and without breaking the shell of or injuring the nuts stamped.

30 A further feature of the invention resides in the provision of a machine of the character described which may be readily adjusted so as to stamp nuts of any size, or other similar objects.

35 With the above and other objects in view, the invention has particular relation to certain novel features of construction, operation and arrangement of parts, an example of which is given in this specification and 40 illustrated in the accompanying drawings, wherein:

Figure 1, is an end view of the device.

Fig. 2, is a rear view, and

Fig. 3, is a plan view thereof.

45 Referring now more particularly to the drawings wherein like numerals of reference designate similar parts in each of the figures, the numeral 1, refers to a suitable framework, having the end legs 2, 2.

50 Located between these legs, there is a drum 3, which is fixed upon the transverse shaft 4, one end of which has the relatively large spur gear wheel 5, fixed thereon. The drum 3 has the peripheral recesses 6, said recesses 55 being arranged in lengthwise rows, the recesses of each row, as well as the rows, being

spaced a uniform distance apart. There is an arm 7 whose lower end has a bearing on the outer end of the shaft 4, and whose upper end is anchored to the framework, 60 and mounted upon this arm are the spur gears 8 and 9, which are in mesh with each other, and the former of which is in mesh with and drives the spur gear wheel 5, while the latter of which is in mesh with and is 65 driven by the spur gear wheel 10. This last mentioned spur gear wheel is fixed upon one end of the transverse shaft 11, which is rotatably mounted in suitable bearings carried by the framework, and fixed upon said last 70 shaft, there is the printing roller 12, whose periphery is preferably formed of rubber or other suitable composition, and is designed to receive the type 13, of the marks or designs to be printed on the nuts 75 or other objects, said type registering with the recesses 6 of the drum 3, as the same rotates. Rotatably mounted in suitable bearings carried by the framework, there is the shaft 14, one end of which has the drive 80 pulley 15, fixed thereon, and provided to receive a belt through which rotation is imparted to it through a suitable motor. This shaft also has a small sprocket wheel 16, fixed thereon, which is in alinement with 85 a corresponding sprocket wheel 17, fixed upon the end of the shaft 11 opposite the spur gear 10, and a sprocket chain 18 operates over these sprocket wheels and transmits rotation from the former to the latter. 90 The numeral 19 refers to distributor which declines from the fixed hopper 20 and which is provided to receive the nuts 21 therefrom. This distributor is suspended by means of links 22, 22, the lower ends of which are 95 pivoted to the framework and the upper ends of which are pivoted to the sides of said distributor. The distributor is formed with chutes 23, arranged parallel and provided to receive the nuts from the hopper 20, and convey them to the drum 3, and deliver them singly into the corresponding recesses 6 as the drum rotates. The sides of each chute are provided with short ribs 24, the ribs of one side of each chute being arranged in staggered relation, relative to those on the other side and said ribs diverge from the center of the chute toward the drum. While any shaped nut or object may be stamped by a machine of this character, 105 the particular design shown is adapted for use in stamping walnuts which are in the 110

form of a prolate spheroid, and as said nuts travel down the chutes, the side ribs, or projections of the shell will engage against the ribs 24, and position said nuts to properly fit in the recesses 6, which have been formed of a shape to conform to the contour thereof. Mounted upon the framework on one side of the distributor, there is a bell crank 25, one arm of which is pivoted to the corresponding side of the distributor, and to the other end of which, one end of the shift rod 26 is pivoted. The other end of this rod is connected eccentrically to the corresponding end of the shaft 14, and as said shaft rotates, said rod 26 is reciprocated, and this reciprocating motion is transmitted through the bell crank 25, to the distributor 19, causing the same to oscillate which results in the downward movement of the nuts along the chutes thereof, and into the recesses of the drum 3.

Rotation is imparted from the drive pulley 15 to the shaft 14, and thence through the sprocket chain 18 to the shaft 11, and the printing roller 12 fixed thereon. Rotation is also imparted from said shaft 11 through the train of spur gears described to the shaft 4, and the recessed drum 3 carried thereby. As the shaft 14 rotates, it operates through the rod 26 to oscillate the distributor 19 through the mechanisms described, and the nuts are thereby fed along the chutes of said distributor and deposited in the recesses of the drum 3, and the type on said printing roller are arranged to register with said nuts and to print the desired mark or design thereon. An inking device 27 of any well known type is employed for supplying ink to said printing roller, and the bearings of the shaft 11 are adjustable, as shown, so that the printing roller may be adjusted toward and from the drum 3, so

that in case the sizes of the nuts vary, the printing roller may be adjusted accordingly, so that it will contact with the surfaces thereof. 45

Fixed on the shaft 14 there is a cylindrical, rotatable brush 28 which engages with the nuts when they reach the lower ends of the chutes 23 and assists in seating them 50 firmly in the recesses 6.

What I claim is:

1. A device of the character described including a rotatable drum, whose periphery is provided with recesses adapted to receive objects, a printing roller mounted for rotation adjacent said drum, means for rotating the drum and printing roller, a distributor provided with delivery chutes along which said objects may be delivered to the corresponding recesses of the drum, lateral ribs carried by the respective chutes, said means being operatively connected with the distributor and oscillating the same to effect the delivery of said objects along said chutes to 65 the recesses of said drum. 55

2. A device of the character described, including a drum, whose periphery is provided with circular rows of recesses adapted to receive objects, a printing roller mounted 70 for rotation adjacent said drum, means for rotating the drum and printing roller, and an oscillating distributor provided with separate chutes for delivering objects to the recesses of the rows which are carried by 75 said drum between it and said printing roller.

In testimony whereof I have signed my name to this specification in the presence of two subscribing witnesses.

FREDERICK B. WISCHHUSEN.

Witnesses:

E. V. HARDWAY,

GEORGE D. ROSEN BROCK.
